ATTORNEY

UNITED STATES PATENT OFFICE.

MARVIN L. BEESON, OF SAN DIEGO, CALIFORNIA.

ROOFING MACHINE

Application filed March 23, 1922. Serial No. 546,028.

To all whom it may concern:

Be it known that MARVIN L. BEESON, a citizen of the United States, residing at San Diego, in the county of San Diego and 5 State of California, has invented a certain new and useful Roofing Machine, of which the following is a specification.

My invention relates to roofing machines, more particularly to machines for laying 10 gravel and paper composition roofing and the objects of my invention are: First, to improve the general form and construction of my roofing machine for which I filed application for Letters Patent in the United 15 States Patent Office June 24, 1921, under the title of Means and methods for preparing roofing, Serial No. 480,127; second, to provide a machine of this class which is easily operated in corners, spaces under ledges and 20 the like; third, to provide a machine of this class which is provided with both a cylindrical roller and a flat shoe for smoothing and packing the asphaltum, tar, paper or any other material that may be used; fourth, 25 to provide a machine of this class which is novelly, efficiently, and economically heated and reduces the danger from fire to a minimum; fifth, to provide a machine of this class which is comparatively light and readily 30 portable; and sixth, to provide a machine of this class which is simple and economical of construction and use, simple of operation, durable, novelly constructed, and which will not readily deteriorate or get out of order.

35 With these and other objects in view as will appear hereinafter my invention consists of certain novel features of construction, combination and arrangement of parts and portions as will be hereinafter described 40 in detail and particularly set forth in the appended claims, reference being had to the accompanying drawings and to the characters of reference thereon which form a part of this application in which:

45 Figure 1 is a side elevational view of my machine showing the shoe in position on the roofing; Fig. 2 is another side elevational view with the roller of my machine in contact with the roofing; Fig. 3 is a top view 50 of my machine; Fig. 4 is a fragmentary

longitudinal sectional view on an enlarged scale through 4-4 of Fig. 1; Fig. 5 is a transverse sectional view through 5-5 of Fig. 4; and Fig. 6 is a fragmentary sectional view through 6-6 of Fig. 5. 55

Similar characters of reference refer to similar parts and portions throughout the several views of the drawings.

The cylinder member 1, heads 2, bushings 3, axle 4, guard 5, guard end plate 6, shoe 7, 60 shoe support 8, plate 9, washers 10, drum supports 11, drum 12, insulating material 13, electrical heating elements 14 and 15, electrical conductors 16 and 17, electrical heating element 18, insulating plate 19, insulating material 20, bearing block 21, screw 22, nut 23, electrical conductor 24, elbow 25, shaft members 26, brackets 27, tie rod 28, Y connection 29, tongue 30, T connection 31, 65 shaft bar 32, and switches 33 and 34 constitute the principal parts and portions of my machine.

The cylindrical roller 1 is provided at each end with a head 2, which head is revolvably mounted on a bushing 3 which bushing is secured to the hollow axle 4 by means of a set screw 3^a. Between the bushing 3 and mounted on said axle are two drum supports 11, secured to the axle by means of set screws 11^a. On said drum supports is 70 mounted a drum 12 about which is wrapped the insulating material 13 which carries the heating element 14 and 15 as shown best in Fig. 4 of the drawings. The drum 12 is secured to drum supports 11 by means of 75 set screws 12^a. Interposed between the bushing 3 and drum supports 11 along the axle 4 are washers 10. Also mounted on the axle 4 are end plates 6 against the outside faces of the bushings 3 said end plates 80 carry the guard 5 which is secured thereto by means of screws 5^a. Secured to said guard end plate 6 are shoe supports 8 by means of screws 8^a. The shoe member 7 is secured to said shoe support by means of 85 screws 7^a. Said shoe is provided with a heating element 18 which is mounted on insulating board or plate 19. Inserted between the inside face of shoe 7 and the heating element 18 is the insulating material 20. 90

100

To secure said heating element in position there is provided a bearing block adapted to rest against the insulating plate. Mounted in the guard member above and in line 5 with said bearing block is a screw 22 provided with a nut 23 which, when screwed in the proper direction secures the same tightly against the bearing block and thus secures the heating element in position. The shoe 10 member is also provided with a plate 9 which is supported by means of screws 9^a at its opposite ends, shown best in Figure 5, and is therefore readily detachable from the shoe support 8 and therefore provides easy 15 access to the interior of said shoe member and therefore to the heating element. The axle 4 is provided at each end with an elbow preferably a standard fitting and secured to the hollow axle by means of set 20 screws 25^a. Inserted in the open end of said elbows are the shaft members 26 which are also held in position against the guard end plate by means of a bracket 27 and secured thereto by screws 27^a. Said guard end 25 plates are provided with a plurality of tapped holes 6^a as shown best in Figs. 1 and 2 of the drawings, which holes are adapted to receive the screws 27^a and therefore permit the shaft members or handles to assume 30 various positions with respect to the shoe member 7, as shown best by the dotted line in Figs. 1 and 2. Shaft members 26 are further held and secured in position by the tie rods 28. Said shaft members are connected at their other ends by means of a Y 35 connection 29. Said Y connection is adapted to receive the tongue 30 on the other end of which is screwed a T connection 31 which is adapted to receive the shaft bar 32. The 40 heating elements 14 and 15 which are in the cylindrical roller are provided with electrical conductors 16 and 17 which extend through the hollow axle 4, then through the shaft member 26 into the hollow tongue 30 45 then through the switch 33 which is connected with a source of electrical energy, such as a power line, not shown on the drawings. The electrical element 18 within the shoe member is also provided with electrical conductors 24 which enter the elbows 50 25 as shown in Fig. 4 of the drawings, then through the hollow shaft members 26 and the tongue 30 to the switch 34 which is also similarly connected.

55 Though I have shown and described a particular construction, combination and arrangement of parts and portions I do not wish to be limited to this particular construction, combination and arrangement but 60 desire to include in the scope of my invention the construction, combination and arrangement substantially as set forth in the appended claims.

It is obvious that with this construction

there is provided a roofing machine which is 65 provided with a cylinder, electrically heated, provided with two elements adapted to be heated independently so that varying heat on the cylinder may be provided; that there is provided a cylinder for rolling as well as 70 a shoe for pressing, which shoe is so shaped that it may be conveniently operated in corners and under ledges and the like; that both the cylindrical member for rolling and the shoe member are electrically heated; that 75 the machine is so constructed that the one is turned up out of the way while the other is in use, that the use of the electrical element, as described, provides a means for 80 heating the operating mechanism which will reduce to a minimum the liability of danger from fire connected with the building; that the machine is small, compact and particularly adapted for roof and small work.

Having thus described my invention what 85 I claim as new and desire to secure by Letters Patent is:

1. A roofing machine of the class described, including a roller revolvably mounted on an axle, electrical heating elements mounted 90 within said roller, a draft means secured to said axle and a guard partially enclosing said roller and secured to said axle.

2. A roofing machine of the class described, including a shoe, enclosed electrical heating elements mounted therein and a draft means in connection therewith.

3. A machine of the class described, including a roller revolvably mounted on an axle, electrical heating elements mounted 100 within said roller, a draft means secured to said axle, a shoe in connection with said roller and electrical heating units mounted in said shoe.

4. A machine of the class described, including a roller revolvably mounted on an axle, electrical heating elements mounted within said roller, a draft means secured to said axle, a guard partially enclosing said 105 roller and secured to said axle; a shoe secured to said guard and electrical heating elements mounted therein.

5. A machine of the class described, including a roller revolvably mounted on a hollow axle, electrical heating elements mounted on a drum within said roller and secured to said axle, a hollow draft means secured thereto, electrical conductors extending through the hollow axle thence through the hollow draft means to switches on the 110 tongue of said draft members.

6. A machine of the class described, including a roller revolvably mounted on a hollow axle, electrical heating elements mounted on a drum within said roller and secured to said axle, a draft means secured thereto, electrical conductors; a guard partially enclosing said roller and also secured 115 120 125

to said axle, a shoe secured to said guard, electrical heating elements mounted in and encased by said shoe, electrical conductors extending through the casing of the latter with a draft member, electrical conductors from the roller heating element extending through hollow axle into said draft members, thence through a tongue of said

draft apparatus to suitable switches on said tongue and power connection to said switches.

In testimony whereof, I have hereunto set my hand at San Diego, California, this 18th day of March, 1922.

MARVIN L. BEESON.
